CHRISTMAS STOCKING

Loretta Reagor, Shreveport, La.

Application June 16, 1950, Serial No. 10,559

Term of patent 3½ years

(Cl. D47—7)

To all whom it may concern:

Be it known that I, Loretta Reagor, a citizen of the United States, residing at Shreveport, in the parish of Caddo and State of Louisiana, have invented a new, original, and ornamental Design for a Christmas Stocking, of which the following is a specification, reference being had to the accompanying drawing, forming part thereof.

Figure 1 is a side elevational view of a Christmas stocking, showing my new design;

Figure 2 is a front elevational view thereof;

Figure 3 is a top plan view of the same; and

Figure 4 is a vertical sectional view through the Santa Claus face of Figure 1 taken on the plane of the line 4—4, looking in the direction of the arrows.

I claim:

The ornamental design for a Christmas stocking, as shown.

LORETTA REAGOR.
